[57] CLAIM

The ornamental design for a set of chess pieces, as shown and described.

DESCRIPTION

FIG. 1 is a perspective view of a set of chess pieces showing my new design;

FIG. 2 is a perspective view of a second embodiment thereof;

FIG. 3 is another embodiment of the middle piece shown in FIGS. 1 and 2;

FIG. 4 is another embodiment of the piece second from the bottom in FIGS. 1 and 2; and

FIG. 5 is another embodiment of the bottom piece shown in FIGS. 1 and 2.

The back of the set of chess pieces is plain and unornamented.

FIG. 3

FIG. 4

FIG. 5
